UNITED STATES PATENT OFFICE.

DONN WOOD, OF NEW YORK, N. Y., ASSIGNOR OF ONE-FOURTH TO WILLIAM L. MARTIN, ONE-FOURTH TO HUGO MANOVILL, AND ONE-FOURTH TO WILLGOTT KLINGBERG, OF NEW YORK, N. Y.

DEVICE FOR MIXING LIQUIDS.

1,175,397.

Specification of Letters Patent. Patented Mar. 14, 1916.

Application filed July 15, 1915. Serial No. 39,940.

To all whom it may concern:

Be it known that I, DONN Wood, a citizen of the United States, residing in the city, county, and State of New York, and whose post-office address is at 98 Morning-side avenue, in said city, have invented certain new and useful Improvements in Devices for Mixing Liquids, of which the following is a specification.

10 My improvements relate to devices which are generally employed for the mixing or compounding of liquids in receptacles, as glasses and in like ways; and the special objects of my improvement are to dispense with the mechanically operated mixing devices, such as by motor, clock work, and intricate gearing, and to simplify and economize in the construction of such a device and for assemblage and dismemberment of 20 the device for cleaning purposes.

One of the special features of my invention is the provision of an apertured dasher cup so designed that upon its downward stroke into the liquid mass, it will force the 25 more or less solid or undissolved contents of the liquid mixture upwardly through the cup, and on its up stroke, by reason of its configuration, will lift a considerable body of liquid and content with it, thereby rapidly and efficiently securing an intimate mixture.

My invention consists in the novel details of construction and combination of parts hereinafter described and further pointed 35 out in the claims.

In the drawing forming part of the specification, Figure 1 is a perspective elevation of a device embodying my improvements; Fig. 2 is a sectional elevation taken centrally 40 through the device, somewhat enlarged, parts being broken away to save room in illustration; and Fig. 3 is a plan view of the dasher cup.

Throughout the various views of the 45 drawings, similar reference characters designate similar parts.

My invention is capable of embodiment in more than one form. The one herein shown, however, has been determined to be practical and efficient for the purposes of my invention.

At 1 is a suitable base and at 2 a standard or pillar erected thereon, the latter being preferably square or rectangular in cross 55 section.

At 3 is a sliding frame consisting of the arms 4, 5, a projection 6 and a squared collar 7. This collar is placed about the pillar 2, and it contains flat springs 8 which frictionally bear against the sides of the pillar. 60 The pillar and bore of the sleeve 7 being square, the latter cannot turn upon the former; at the same time it can be moved up and down unrestrictedly and with it all the parts hereinafter described, which are attached to it. These latter may be bodily removed from the pillar for the purpose of dismemberment, cleansing or repair. The ends of the arms 4, 5, are apertured, as at 65 9. Between these arms extend a cylindrical 70 casing 10. Through the casing and the apertures 9 in the arms 4, 5, extends a rod 11. Above the arm 4 the rod is provided with a removable disk 12.

At 13 is a cup-cap of usual construction 75 which is designed to lie over glass as 14, and in the usual manner retain the contents in the glass. A stud 15 on the base 1 assists in the positioning of the glass.

The rod 11 extends through an aperture 80 formed in the top of the cap 13, and has secured to its lower end by means of a nut 16 and a screw thread 17 on the rod, a dasher cup 18. This cup is bell-shaped with its open end extending downwardly and is 85 provided with a series of apertures 19, 20, the apertures 19 being preferably circular and disposed adjacent the lower edge of the cup and the apertures 20 being preferably rectangular and upwardly elongated and located intermediate of the crown 21 of the cup and its lower edge 22. The cup may be otherwise apertured, but I prefer the above described arrangement, for the reason that the circular apertures 19 will force the more 90 freely movable solids or non-dissolved ingredients, such as sugar and the like, up through the cup, while the upwardly elongated apertures 20 will allow of a considerable quantity of liquid passing up and 95 through the cup as well as carrying with it other pieces of floating solid material.

Inside of the casing 10 is a coil spring 23 which embraces the rod 11, one end of the spring resting against the upper face of the 105 arm 5, the upper end bearing against a washer 24 which surrounds the rod 10, a pin 25 serving to keep the washer in position.

In the operation of the device, the frame 6 is raised and the glass 14 containing the 110

mixture is placed upon the base 1, its lower edge striking the projection 15. Then the frame is lowered until the cap 13 covers and engages the glass for the purpose above described. Particularly the weight of the frame bearing on the cap retains the latter in place. By a series of quick blows or thrusts on the disk 12, the dasher cup is forced down into the liquid, operating as above described to thoroughly mix and intermingle the contents. After the mixing has been completed, the frame 6 is raised so as to free the glass from the dasher cup and cap 13, the springs 8 holding the frame in its elevated position.

The parts are specially designed so that they may be removed for cleansing purposes. This can be accomplished by merely unscrewing the disk 12, removing the pin 25 when the rod 11 can be withdrawn and the casing 10 and spring removed. They may then be cleaned and the parts reassembled by reversing the order above referred to.

While I have shown one form of my invention, it is susceptible of various modifications without departing from its spirit, so I do not desire to be limited to the exact construction shown and described herein, but consider my invention as broad as the scope of the claims appended hereto.

Having described my invention, I claim:

1. In a device of the class described, the combination with a base, a pillar thereon, a frame slidable upon said pillar, a rod movable in said frame, a spring for retracting said rod when the same has been forced

down, a casing in the frame and surrounding said spring, a dasher on the lower end of said rod, and a receptacle cap held on the receptacle by the weight of said frame. 40

2. In a device of the class described, the combination with a base, an upwardly extending pillar mounted on said base, a frame movable on said pillar, a pair of arms on said frame, a hollow cylindrical casing extending between said arms, a rod extending through perforations formed in said arms and through said casing, a spring in said casing surrounding said rod, a stop on said rod against which the upper end of the spring abuts, a dasher cup secured to the lower end of the rod and a cup cap, having an opening through which the rod extends, between the dasher and the frame. 45

3. In a device of the class described, the combination with a base, a pillar mounted on said base and extending upwardly therefrom, a movable frame mounted on said pillar, a pair of arms on said frame, one of said arms being disposed above the other, a cylindrical casing between the ends of said arms, a rod extending through perforations formed adjacent the ends of said arms and through the casing, a coil spring within said casing and surrounding said rod, one end of said coil spring resting on the lower arm on the frame, the other end abutting against a pin on said rod and a bell-shaped dasher on the lower end of said rod. 50

Signed at the city, county and State of 70
New York, this 13th day of July, 1915.

DONN WOOD.
